UNITED STATES PATENT OFFICE.

WILLIAM NOAH ARNOLD, OF OMEN, TEXAS.

COMBINED CORN-PLANTER AND FERTILIZER-DISTRIBUTER.

SPECIFICATION forming part of Letters Patent No. 293,615, dated February 19, 1884.

Application filed October 6, 1883. (No model.)

To all whom it may concern:

Be it known that I, WILLIAM N. ARNOLD, a citizen of the United States, residing at Omen, in the county of Smith and State of Texas, have invented a new and useful Combined Corn-Planter and Fertilizer-Distributer, of which the following is a specification, reference being had to the accompanying drawings.

This invention relates to combined corn-planters and fertilizer-distributors; and it has for its object to produce a machine which shall possess superior advantages in point of simplicity, durability, and general efficiency.

To this end my invention consists in certain improvements in the construction of the said machine, which will be hereinafter fully described, and particularly pointed out in the claims.

In the drawings hereto annexed, Figure 1 is a perspective view of my improved combined corn-planter and fertilizer-distributer. Fig. 2 is a longitudinal vertical sectional view of the same. Fig. 3 is a horizontal sectional view taken on the line $x-x$ in Fig. 2, and Fig. 4 is a bottom view.

The same letters refer to the same parts in all the figures.

A in the drawings designates a suitable frame, in the sides of which is journaled an axle, B, having the transporting-wheels C C. The frame A is provided with longitudinal bars D D, supporting the hopper E, and it has at its front end the tongue F, to which the shank G of the furrow-opener H is suitably secured and braced. The hopper E, which is designed to contain the fertilizing material, is provided with a transverse shaft, I, which is provided with radial stirring or agitating fingers J J. One end of the said shaft extends through the side of the hopper, and carries a pinion, K, meshing with a spur-wheel, L, upon the axle B, from which motion is thus transmitted to the agitating-shaft when the machine is in operation. The bottom of the hopper E is formed by a pair of plates or levers, M and N, pivoted upon the longitudinal bars D D, under opposite sides of the hopper, and meeting centrally under the same, so as to form a complete bottom. One end of the lever M has an arm, O, which is connected by a pivoted rod, P, with an arm, Q, extending from the lever N. The arm O is also connected with

the front end of the frame A by a traction-spring, R, which serves to keep the bottom of the hopper normally in a closed position. The other end of the lever M has an arm, S, extending so as to engage blocks or bars T, secured on the inner side of the adjoining wheel C when the latter revolves.

The operation of this part of the invention will be readily understood. When the machine is in operation, the bars T upon the wheel C will strike the arm S of lever M, thereby forcing the latter in a forward direction. The arm O of said lever, being connected by rod P with the lever N, will at the same time force the latter in a rearward direction, thus opening the bottom of the hopper and causing a portion of its contents to escape, the stirrers or agitators serving to prevent the fertilizing material from packing. When the bar T has passed the arm S, the spring R, exercising its tension upon the arm S, automatically closes the bottom of the hopper and retains it until the next bar, T, reaches arm S.

Secured between the bars D D, under the rear plate or lever, N, is a plate, U, and a seed-hopper, V, is suitably mounted above the said lever N. The latter is provided with an opening or seed-cup, W, of suitable size, and adapted, when the lever N is moved rearwardly, to register with the seed-opening X in the bottom of the hopper. The bottom plate, U, has an inclined opening or chute, Y. When the lever N moves back, its seed-cup W receives the seed from the hopper, and when, by the action of the spring, as described, it is moved in a forward direction, the seed is suddenly and forcibly thrown through the chute Y, the incline of which is so gaged that the seed shall be deposited on top of the fertilizing material, which has been dropped by the same action of the levers.

The rear end of the frame A carries shanks Z, having coverers A', and a drag or leveler, B', may be used when desired.

The operation and advantages of this invention will be readily understood from the foregoing description, taken in connection with the drawings hereto annexed. It is simple in construction, easily managed, and effective in operation.

I claim as my invention and desire to secure by Letters Patent of the United States—

1. The combination of the frame, the revolving axle having transporting wheels, blocks or bars upon the inner side of one of the latter, longitudinal frame-bars, a hopper 5 mounted upon the same, a pair of levers or plates pivoted upon the longitudinal frame-bars, under opposite sides of the hopper, and forming the bottom of the latter, arms extending from the said levers and connected by a pivoted rod, a spring connecting the arm of the front lever with the front part of the frame, and an arm extending from the opposite side of the front lever and adapted to engage the blocks or bars upon the inner side of the adjoining transporting-wheel, substantially as set forth.

2. In a combined corn-planter and fertilizer-distributer, the combination of a hopper, a pair of levers, forming the bottom of the same, mechanism for moving or opening the said levers in opposite directions, so as to permit the escape of a portion of the contents of the hopper, a seed-hopper arranged in rear of the main hopper above the rear lever, a seed-25 cup formed in the latter, a bottom plate hav-

ing an inclined opening or chute, and mechanism for automatically closing the levers or bottom plates of the main hopper, substantially as set forth.

3. In a combined seed-planter and fertilizer-distributer, the combination of the seed-hopper, the seed-slide consisting of a lever, which forms part of the bottom of the fertilizer-hopper, mechanism for moving the said lever or seed-slide in a rearward direction to receive seed from the hopper, a spring arranged to move the said lever or seed-slide in a forward direction by a quick and sudden action upon the cessation of the actuating mechanism, and a bottom plate having a forwardly-inclined opening or chute, through which the seed will be thrown by the forward action of the seed-slide, as and for the purpose set forth.

In testimony that I claim the foregoing as my own I have hereto affixed my signature in 45 presence of two witnesses.

WILLIAM NOAH ARNOLD.
